John H. Barker
ATTORNEY

UNITED STATES PATENT OFFICE.

EDWARD BERGQUIST, OF NEW YORK, N. Y.

FOUNTAIN PEN.

Application filed July 20, 1922. Serial No. 576,368.

To all whom it may concern:

Be it known that I, EDWARD BERGQUIST, a subject of King Gustaf V of Sweden, and a resident of the borough of Bronx, in the 5 county of New York and State of New York, have invented certain new and useful Improvements in Fountain Pens, of which the following is a full, clear, and exact description, whereby anyone skilled in the art may 10 make and use the same.

The invention hereinafter described is directed to fountain pens and particularly to the type of pen termed in the art a "self filling pen."

15 Self filling pens in the art, are not new, and generally consist of a pen barrel within which is arranged a flexing tube serving as the ink "fount" or container. In such devices, it is customary to provide a means for 20 collapsing the flexible tube to cause a partial vacuum within the ink "fount" and when the pen point and feed are immersed in the ink, and pressure is released from the collapsed tube, a suction is effected which draws 25 the ink into the "fount" of the pen.

Such devices have inherent objections in 30 that there is a boiling or surging of the ink due to its admixture with air bubbles. A further objection results from the use of the flexible tubes which soon become impaired. 35 A still further objection is due to the limited capacity of the "fount" as compared with the normal sized barrel or casing which has become practically standard size in pens.

With the above recitation of general conditions, it will be apparent, as hereinafter disclosed, that the main object of the present invention is to provide a pen having a maximum "fount" capacity for a given barrel 40 size; that there shall be a complete filling of the "fount"; that liability of surging and air bubbles will be obviated; and that the pen may be readily and completely cleansed of its charge and readily washed and cleansed.

45 A further object is to provide an arrangement of parts so that no error may occur in the filling of the pen and when filled will maintain its charge without leakage. Provision is also made for preventing "sweating" and consequent improper discharge of ink from the pen.

Referring to the drawings: Figure 1 is a view in elevation with the cap cut in sections.

50 Figure 2, is a vertical sectional view showing the parts in position to receive a charge of ink.

Figure 3, is a similar view illustrating the parts as they are forced together to draw in the charge of ink.

Figure 4, illustrates a preferred form of 60 leak proof joint.

Self filling pens have been heretofore designed but have had no effective means by which they could be thoroughly cleansed and scavenged of any residual charge of ink. As 65 a result, the constant taking in of new charges is contaminated with the old residual charge; therefore, the pen soon becomes foul and fails to operate properly.

It is one of the objects of the present device to provide a sliding piston arrangement by which the "fount" of the pen will be entirely exhausted of its charge upon withdrawal of one of the "fount" members preparatory to the filling operation. This arrangement contemplates a downward movement of the members which will place them in position of final assembly ready for use. It is not necessary to elevate the pen point in order to prevent flooding. 80

In carrying out the invention in one form, as illustrated in the drawings, I provide the usual barrel 1, with its screw cap 2, which protects the pen 3, and feed 4. These parts may be of any desired form to meet requirements. 85

Screw threaded, or otherwise secured to the barrel 1, is the tip 5, within which is supported the pen point 3, and feed 4. There is the usual feed duct 6, communicating with the ink "fount" to deliver ink to the pen. 90

The ink "fount" consists of an inner tube 7, and an outer tube 8. The inner tube 7, is secured in any suitable manner to the tip 5, and extends into the outer tube 8, through 95 a stuffing box or packing 9.

This stuffing box is conveniently formed by the pressing of annular groove 10, in the wall of the outer tube 8, and inserting a suitable packing such as cork, as indicated 100 at 11. The outer end of the tube 8, is then spun over the end of the packing as at 12. This provides a convenient form of leak proof joint between the inner tube 7, and outer tube 8. 105

The inner tube 7, at its upper end is provided with a piston packing 13, preferably of compressed cork, which fits snugly within the tube 8.

Just below the piston packing 13, are vent 110 openings 14, which form a communication between the interior of the inner tube 7, and

the interior of the outer tube 8, below the piston packing 13. There may be a plurality of these openings 14, only one being illustrated in the drawings.

5 The main barrel 1, has an interior diameter slightly larger than the exterior diameter of the outer tube 8, thus providing an air gap or space which effectually prevents expansion of the ink charge and consequent 10 leakage or overflow at the pen point.

The upper end of the tube 8, has secured to it a cap or plug 15, which, as illustrated, is screw threaded as at 16, to engage the screw threaded opening 17, in the upper end of 15 the barrel 1.

This screw threaded plug serves to hold the parts together when the pen is filled. Screw threads are illustrated, although it is obvious that any form of interlocking parts 20 may be employed.

There is a perforation or vent 18, in the cap or plug 15, through which air above the piston 13, may be exhausted from the outer tube 8, as it is forced down to create a 25 partial vacuum in the ink "fount."

The operation of the device will be at once apparent on the examination of Figures 2 and 3, of the drawings.

When the outer tube 8, is fully drawn up 30 after releasing the screw threaded cap, the piston 13, will rest against the annular depression 10, in the lower end of the tube 8.

In this position, the opening 14, will lie 35 within the packing 9, and the "fount" will obviously be entirely exhausted of its charge.

Figure 2, illustrates the parts about to fully discharge by upward movement of the tube 8.

40 The pen point is now introduced into the ink and a depression of the tube 8, causes first a partial vacuum in the tube 7, and as the former is forced down over the piston 13, a sufficient suction is induced to completely fill the tube 7, and the chamber of 45 the tube 8, which lies below the piston packing 13.

The tubes 7, and 8, are preferably formed of a noncorroding metal which permits the use of very thin walls and therefore leaves 50 a maximum "fount" space.

Attention is particularly directed to the arrangement by which a withdrawal of the actuating tube 8, causes an exhausting of the "fount" chamber while a depression of the 55 tube 8, within the barrel causes a filling of the "fount" and leaves the parts in final position for use with the "fount" completely filled. Due to the suction effect of the partial vacuum, there is no liability of leakage 60 when the pen point is withdrawn from the ink after the filling operation.

Owing to the thinness of the walls of the telescoping tubes, it is feasible to provide the air chamber between the barrel 1, and 65 the ink "fount" members. This air gap

serves as an insulating medium for preventing sweating of the "fount" or expansion of its charge due to atmospheric changes from the heat of the body or hand while carrying the pen or using it. Furthermore, the use of the telescoping "fount" tubes permits of a light and very cheap construction as compared with any attempt to use the generally adopted hard rubber. It is practically impossible to fashion hard rubber to effect the results attained as hereinbefore described.

Obviously, the exact details of construction, fashioning of joints and connections, etc., may be varied to suit the exigencies of any particular requirements.

The main purpose of the invention is specified by the use of the telescopic tubes, pistons and interconnecting openings such as has been described.

Attention is particularly directed to the unique stuffing box connection between the inner tube 7, and outer tube 8.

The packing 9, being of compressed cork, must, in order to withstand the spinning operation without distortion, be backed up by washers such as illustrated at A and B.

Washer A, is dropped into the end of the tube 8, and rests against the shoulder formed by the annular depression 10. The cylinder of compressed cork is then inserted and a washer B, is laid over its outer end. The end of the tube 12, is then spun over the washer B. It will be apparent that without such provision, the cork would become distorted, would not give a proper fit, and would prevent the spinning of a clean joint at the end of the tube. The features are illustrated at Figure 4, of the drawings.

It will be observed that the inner tube 7 is of comparatively large diameter, with the result that the ink reservoir formed thereby is of a capacity equal to or approximately equal to the capacity of the space between the two tubes 7 and 8 and between the piston 13 and the packing 9. There are practical advantages incident to this arrangement.

I have found that when the inner tube is of small size it becomes necessary to pull out the outer tube 8 from time to time in order to maintain the flow of ink, or working condition of the pen, and that unless this is very carefully done such movement will cause a "bleeding" of the pen, because a very slight movement of the outer tube causes a rapid flow of ink through the inner tube when it is of very small size.

With my arrangement, however, where the inner tube is of relatively large size, it not only serves as a reservoir for a relatively large portion of the ink charge of the pen, but when that has been used all that is necessary in order to renew the supply of ink in the tube 7 is to invert the pen, whereupon the ink within the chamber between

the two tubes 7 and 8 will freely flow, through the openings 14, which are of fairly large size, into the inner tube 7. This 5 manner when the inner tube is of small diameter, because, as I believe, of the capillary action of the ink upon the walls of the inner tube interfering with the free flow of ink into the small inner tube, except as 10 it may be aided by air pressure due to relative sliding movements of the two telescoping tubes constituting the "fount" of the pen.

What I claim as my invention and desire 15 to secure by Letters Patent is:

1. In a fountain pen, a pen barrel, an ink "fount" arranged within the barrel, said "fount" consisting of a pair of telescopic tubes of different diameters, the inner tube 20 communicating with the pen point, and being of a relatively large diameter whereby it serves as a reservoir for a relatively large portion of the ink charge, a piston packing upon the inner tube, a leak proof packing 25 between the inner and outer tubes, said inner tube having perforations below the piston packing providing a free communication between the interior of the inner tube and the interior of the outer tube.

2. In a fountain pen, a pen barrel, an ink "fount" arranged within the barrel and consisting of a pair of telescoping tubes, a piston packing and a leak proof packing between the tubes, one carried by each, there 35 being perforations through the inner tube constituting a free communication between it and the space enclosed by the outer tube between the said packings, the relative sizes of the two tubes being such that the capacity of the inner tube and the communicating 40 chamber enclosed by the outer tube are

approximately equal when the tubes are telescoped together.

3. In a fountain pen, a pen barrel, a removable tip and feed, an ink "fount" 45 communicating with the feed, said ink "fount" comprising a pair of telescopic tubes, one of said tubes having a packing forming a piston, the outer tube of the "fount" being of less diameter than the interior diameter of 50 the barrel, whereby the entire ink "fount" or reservoir is insulated by an air space from the outer barrel of the pen, openings communicating with the interior of the inner tube and outer tube, and an air vent 55 communicating with the outer tube.

4. In a self-filling fountain pen, a pen barrel, tip, feed, and pen point, an ink "fount" arranged within the barrel comprising a sliding tube having an external 60 diameter less than the internal diameter of the barrel, whereby an air chamber is provided between the barrel and the ink "fount."

5. An ink "fount" for fountain pens 65 consisting of an inner tube member and an outer tube member, a piston packing between said members, a leak proof joint between the inner and outer tubes, said joint comprising an annular depression in the 70 outer tube, a washer resting against the shoulder formed by said depression, a cork packing, a washer at the outer end of the packing, and an inturned flange at the end of the tube bearing against said outer 75 washer whereby the washers support the tube wall and permit compaction of the packing.
